UNITED STATES PATENT OFFICE.

GEORGE E. RUNYON, OF KANSAS CITY, KANSAS, ASSIGNOR OF ONE-HALF TO GLEN HAZEL, OF KANSAS CITY, KANSAS.

ROLLER BEARER.

Application filed February 20, 1922. Serial No. 537,757.

To all whom it may concern:

Be it known that I, GEORGE E. RUNYON, a citizen of the United States, residing at Kansas City, in the county of Wyandotte 5 and State of Kansas, have invented certain new and useful Improvements in Roller Bearers, of which the following is a specification.

My invention relates to roller bearers 10 adapted to be applied to printers' chases for the purposes of supporting the ink distributing rolls of the printing press type-high during their travel over the form locked up in the chase.

15 Heretofore, it has been customary to support the distributing rolls by the metal rollers at each end thereof. Said metal rollers travel on the tracks forming part of the press and have sufficient traction to drive 20 the associate distributing rolls. Under favorable temperatures this old method is more or less satisfactory, but when the relatively sensitive distributing rolls are subjected to changes in temperature which 25 cause them to expand or contract and thus become larger or smaller diametrically than the metal rollers, too much or too little ink is applied to the type and results in unsatisfactory printing.

30 By the use of my invention the distributing rolls are held type-high while traveling over the form, irrespective of diametrical variations and said distributing rolls have sufficient traction on the roller bearers constituting the present invention, to prevent 35 slippage and consequent uneven distribution of the ink upon the type.

A further feature of the invention resides 40 in the fact that my roller bearers are applied to the outside of the chase instead of being locked up with the form, and hence just as soon as the chase is removed from the press the roller bearers can be removed instead of waiting for the form to be 45 removed from the chase, where it sometimes remains for several days. Thus a less number of roller bearers are required in the printing shop.

Other features will hereinafter appear, 50 and in order that the invention may be fully understood, reference will now be had to the accompanying drawing, in which:

Fig. 1 is a plan view of a chase equipped 55 with my roller bearers upon which two of the distributing rolls are mounted.

Fig. 2 is a fragmentary cross section on line II—II of Fig. 1.

Fig. 3 is a side elevation of the chase with the roller bearers in position thereon.

Fig. 4 is a detail perspective view of one 60 of the roller bearers.

Referring now in detail to the various parts, A designates a chase in which a form B is locked. D designates the ink distributing rolls equipped at their ends with metal traction rollers E, which travel on the tracks F of the printing press.

All of the foregoing are of usual construction, the present invention residing in the roller bearers 2, which are removably applied to the opposite ends of the chase A to hold the distributing rolls D type-high.

Each roller bearer 2 consists of a rail 4 tapered at its ends as indicated at 6, so that the distributing rolls D can readily mount 75 and leave the track formed by the rails 4.

Each rail 4 is equipped adjacent to its ends with holders 8, which are substantially C-shaped in cross section to snugly engage the top, bottom and outer surfaces of the end bars G of the chase A, as shown more clearly by Fig. 2. The holders 8 may be secured to the rails 4 in any suitable manner. In the drawings I have shown their upper portions countersunk in the lower portions of the 85 rails 4 and firmly secured to the latter by screws 10.

In practice the roller bearers 2 are applied to the outside of the bars G of the chase A, instead of being locked up with the form B and the parts are so proportioned that the upper surfaces of the rails 4 are type-high, so that when the distributing rolls D travel on said rails 4 they will be supported type-high irrespective of any diametrical changes which may have occurred due to changes in temperature, and hence uniform distribution of the ink upon the type is assured.

When the chase A is removed from the 100 printing press the roller bearers 2 can be slipped off the ends of said chase A without waiting for the removal of the form B, and applied immediately to another chase ready for the press.

From the foregoing description it will be understood that I have provided simple devices which are well adapted for the purpose intended, and while I have shown and described the preferred form of my inven- 110

tion, I reserve the right to make such changes as properly fall within the spirit and scope of the claim.

Having thus described my invention, what I claim and desire to secure by Letters Patent, is:

An attachment for printers' chases consisting of a pair of rails adapted to lie on top of the end bars of said chase, and holders

of substantially C-shape in cross section 10 fixed to said rails to removably secure the same to the chase.

In testimony whereof I affix my signature, in the presence of two witnesses.

GEORGE E. RUNYON.
